UNITED STATES PATENT OFFICE.

WOLFGANG E. SCHWARZMANN, OF SPRINGFIELD, MASSACHUSETTS, ASSIGNOR, BY
MESNE ASSIGNMENTS, TO AMERICAN BOSCH MAGNETO CORPORATION, OF NEW
YORK, N. Y., A CORPORATION OF NEW YORK

IGNITION-TIMING MECHANISM.

1,375,263.

specification of Letters Patent. Patented Apr. 19, 1921.

Application filed September 26, 1917. Serial No. 193,242.

To all whom it may concern:

Be it known that I, WOLFGANG E SCHWARZMANN, a citizen of the United States, residing at 51 Bellclaire avenue, 5 Long Meadow, Springfield, in the county of Hampden, State of Massachusetts, have invented certain new and useful Improvements in Ignition-Timing Mechanism; and I do hereby declare the following to be a 10 full, clear, and exact description of the invention, such as will enable others skilled in the art to which it appertains to make and use the same.

An ignition system almost invariably provides variable timing periods to suit the different speed and load conditions imposed on the engine with which it is associated. To do this, the mechanical interrupter of the magneto or the sparking coil has an adjustable member to which is attached a timing member connected by an adjusting wire or rod to the control lever on the steering wheel of a moving vehicle or a convenient part of a stationary organization. It has been customary heretofore to fasten a timing arm to the adjustable member of the interrupter by a screw or other device rigidly connecting them together, but in that arrangement the adjusting pull on the control lever is applied at a single point of the periphery of the adjustable member and sometimes causes the adjustable member to bind in its bearing, particularly if a decided increase in the resistance develops in the bearing.

It is often necessary for the timing member to be located on one side or the other of the adjustable member of the interrupter or above or below it, or at some intermediate point, in order that the adjusting wire or rod from the control lever may be attached to it most conveniently. Ordinarily the adjustable member of the interrupter carries cams which are periodically engaged by the deflectable one of the pair of rotatable interrupter elements. Since these cams must be accurately positioned relatively to each other, they are fastened in the adjustable member by the manufacturer of the mechanical interrupter, and therefore the engine builder is often inconvenienced in installing the magneto or the adjusting wire or rod. To meet this contingency, the adjustable member of the interrupter has been provided with several longitudinal slots into a

selected one of which is set a lug or feather carried by the timing ring, and to the timing ring is attached a timing arm connected to the adjusting wire or rod. While this arrangement provides several positions of connection, it requires a thicker adjustable member to provide for the slots, and it results, as before, in a single point of application of the adjusting pull to the adjustable member. Furthermore, the timing ring is not positively prevented from working off from the adjustable member in an axial direction as a result of the continual vibration to which it is subjected by the engine.

In accordance with my invention, the timing member comprises a ring having wedge teeth meshed with wedged teeth on the adjustable member of the interrupter so as to positively interlock or engage therewith at a plurality of points around their periphery, and an arm fast with the timing ring for connection to the adjustable wire or rod from the control lever. This arrangement distributes the adjusting pull of the control lever around the periphery of the adjustable member, and so also the timing ring may be connected to the adjustable member in substantially any angular relation desired. These results are nicely attained in the preferred embodiment hereinafter described as an example of my invention, by nurling a ring on the outer surface of the adjustable member of the interrupter and broaching the inner surface of the timing ring, the timing ring and a portion of the timing arm being split so as to be capable of contraction and expansion diametrically in connecting and disconnecting the parts. By nurling the ring intermediate of the end faces of the adjustable member, the side ledges of the knurled portion positively prevent the contracted timing ring from working off the adjustable member in an axial direction.

In the accompanying drawings, illustrating this preferred embodiment of my invention in application, as an example, to a magneto,

Figure 1 is an end view of a magneto showing the timing member in position on the adjustable cam member of a mechanical interrupter, the cover of the interrupter being removed; Fig. 2 is a view, partly in section and partly in elevation, of the tim-

ing member in place on the adjustable member; and Figs. 3 and 4 are perspective views of the timing member and the cam member, respectively.

5 The magneto 1 is provided with a mechanical interrupter comprising an insulated interrupter element 2, a grounded insulated interrupter element 3 coöperative therewith, and a cam member 4 carrying the interrupting cams 5 fastened to it. The interrupter elements 2, 3 are mounted on the interrupter disk 6 rotatable with the magneto shaft 7. The cam member 4 is journaled in a bearing in the magneto housing 8 for adjusting movements through an angle determined by the slot 9 and a pin projecting thereinto from the magneto housing, and it is held in its bearing by a pivoted spring finger 10 pressing the cover 11 over the outer end face of the cam member. The interrupter element 3 is deflected periodically, upon engagement of the fiber block 12 with the cams 5, to separate it from the coöperative element 2 and thereby interrupt 25 the circuit of the magneto winding during its period of maximum voltage generation. These features are well known in the art.

The cam member has a knurled ring 13 intermediate its end faces. The timing ring 14 has its inner surface broached at 15, and has integral with it a timing arm 16 with a perforated boss 17 to which is connected the adjusting rod or wire 18 extending to the control lever on the steering wheel of a moving vehicle or to a convenient member of a stationary organization. The timing ring and a part of the timing arm are split at 19 and the clamping screw 20 passing through the split portion is adapted to contract or 40 expand the timing ring. The knurled ring 13 and the broached surface 15 have meshed wedge teeth positively interlocking or engaging at a plurality of points around their periphery to hold the cam member and the timing ring in substantially any angular relation desired, whenever the ring is clamped onto the cam member by the clamping screw 20.

The timing ring 14 is somewhat narrower than the knurled ring 13 so that when the knurled and broached surfaces are meshed, the side ledges 21 of the knurled ring act as abutments to the side faces 22 of the broached surface and thereby prevent the ring from working off from the cam member in an axial direction as a result of vibration.

To connect the timing ring in any desired relation with the cam member, the ring is 60 expanded by the screw 20 until its inner diameter exceeds the outer diameter of the cam member. The timing ring is then slipped over the cam member until the wedge teeth of its broached surface are in 85 position to mesh with the wedge teeth of the

knurled ring, in the angular relation desired. By taking up on the clamping screw, the two surfaces are then meshed substantially all around their periphery and provide interlocking or engaging surfaces at a plurality of points around their periphery. The timing ring may be removed from the cam member merely by sufficiently loosening the clamping screw and pulling the timing ring off from the cam member in an axial direction.

Having thus described my invention, what I claim is:

1. In variable timing mechanism for mechanical interrupters for ignition apparatus, an adjustable member carrying one of the elements of the mechanical interrupter and having wedge teeth on its periphery, a timing member comprising an arm and a ring connected to the arm and having wedge teeth adapted to mesh with the wedge teeth on the adjustable member, and means for contracting and expanding the ring around the adjustable member, whereby the ring and the adjustable member may be meshed around their peripheries with the arm extending in any desired angular relation to the adjustable member for connection to an adjusting wire or rod. 85

2. In variable timing mechanism for mechanical interrupters for ignition apparatus, a cam ring having wedge teeth entirely around its outer periphery, a timing member comprising an arm and a ring connected to the arm and having wedge teeth entirely around its inner periphery adapted to mesh with the cam ring, and means for contracting and expanding the ring around the cam ring, whereby the cam and timing rings may be meshed around their peripheries with the arm extending in any desired angular relation to the cam ring for connection to an adjusting wire or rod. 95

3. In variable timing mechanism for mechanical interrupters for ignition apparatus, an adjustable member carrying one of the elements of the mechanical interrupter and having wedge teeth on its periphery, a timing member comprising a ring and an arm connected to the ring and being broached to mesh with the adjustable member, and means for contracting and expanding the ring around the adjustable member, whereby the ring and the adjustable member may be meshed around their peripheries with the arm extending in any desired angular relation to the adjustable member for connection to an adjusting wire or rod. 110

4. In variable timing mechanism for mechanical interrupters for ignition apparatus, an adjustable member carrying one of the elements of the mechanical interrupter and having wedge teeth on its periphery, a timing member comprising an arm and a split ring connected to the arm and having 125 130

- wedge teeth adapted to mesh with the wedge teeth on the adjustable member, and a screw for contracting and expanding the timing ring around the adjustable member, whereby the ring and the adjustable member may be meshed around their peripheries with the arm extending in any desired angular relation to the adjustable member for connection to an adjusting wire or rod.
- 10 5. In variable timing mechanism for mechanical interrupters for ignition apparatus, an adjustable member carrying one of the elements of the mechanical interrupter and having wedge teeth on its outer periphery intermediate the end faces thereof and
- extending below the outer surface to form side ledges, a timing member comprising an arm and a ring connected to the arm and having wedge teeth on its inner surface, and means for contracting and expanding the 20 ring around the adjustable member between the side ledges, whereby the ring and the adjustable member may be meshed around their peripheries and held sidewise with the arm extending in any desired angular relation to the adjustable member for connection to an adjusting wire or rod. 25

In testimony whereof I affix my signature.

WOLFGANG E. SCHWARZMANN.
